PIPE ORGAN

Filed April 15, 1929

FIG. 1

FIG. 2

INVENTOR
H. F. WATERS

BY *Frank Harrington*
ATTORNEY

UNITED STATES PATENT OFFICE

HARRY F. WATERS, OF WINDHAM COUNTY, VERMONT

PIPE ORGAN

Application filed April 15, 1929. Serial No. 355,246.

This invention relates generally to pipe organs and more specifically to an improved portable pipe organ adapted for home or theatre use, the predominant object of the 5 invention being to produce an improved pipe organ of this type which is shaped to conform substantially to the shape of a grand piano.

Of late years there has been a great demand 10 for pipe organs of modern construction which might conveniently be used in homes and in smaller theatres of insufficient dimensions to give the necessary space to a modern pipe organ of the common and well known type. 15 Also there has been a demand for a portable pipe organ which might be moved onto a stage for a concert by an organist.

Prior to this invention no portable pipe organ of modern construction has been produced 20 which would meet the needs referred to above and I have, therefore, devised the pipe organ disclosed in the present application, which briefly stated has the shape and general appearance of a grand piano. My 25 improved pipe organ includes a casing which has the shape referred to and within this casing I arrange all of the pipes, the wind chest, valve units, and all other elements which go to make up the complete organ. In short, 30 except for the keyboard and a portion of the casing at the bottom of the forward portion thereof, my improved pipe organ is an exact reproduction of a grand piano, hence, the pipe organ disclosed herein has all of the 35 beauty of a grand piano and may be moved about as a unit with equal facility.

Figure 1 is a view partly in side elevation and partly in vertical section showing my improved pipe organ.

40 Figure 2 is a front elevation of the pipe organ shown in Figure 1, portions of the casing thereof being broken away to reveal the interior construction and arrangement of the pipe organ.

In the drawings, wherein is shown for the purpose of illustration merely one embodiment of my invention, A designates my improved pipe organ which comprises a casing 1 shaped to resemble a grand piano, said casing comprising the usual body portion 2 sup-

ported on pairs of forwardly positioned legs 3 and a pair of rear legs 4. At the pairs of forward legs 3, the casing 1 is provided with a downwardly extended portion 5, said downwardly extended portion being produced by 55 rectangularly arranged walls 6 which produce a chamber or compartment 7 preferably open at the bottom. The walls 6 are fixed to the legs 3 of the casing and as a result the downwardly extended portion 5 is an integral 60 part of the casing.

Located in the chamber or compartment 7 within the downwardly extended portion 5 of the casing preferably at the bottom thereof is the wind chest 8 of my improved pipe 65 organ, said wind chest being of the construction common to wind chests of pipe organs and being supported preferably by being attached in any suitable manner to the rectangular walls 6 of the downwardly extended 70 portion 5 of the organ casing. The wind chest 8 will have associated with it suitable means for forcing air into the wind chest under pressure. This means may be of any desired construction and may be manually, 75 mechanically or electrically actuated and controlled, but as such means are of well known construction and arrangement I do not deem it necessary to illustrate or describe same herein.

Arranged within the compartment or chamber 7 and immediately above the wind chest 8 therein is a row of relatively short pipes 9. This row of pipes extends transversely of the organ at a point adjacent to the forward portion of the wind chest 8 and said pipes are disposed perpendicularly throughout their entire length as shown in Figure 1. Located within the compartment or chamber 7 rearwardly of the row of pipes 9 are three rows of pipes which are designated by the reference characters 10, 11 and 12. The rows of pipes 9, 10, 11 and 12 are spaced from front to rear of the compartment or chamber 7 as shown in Figure 1 and the pipes of the respective rows of pipes are spaced transversely of the organ as shown in Figure 2. Each pipe of the rows of pipes 10, 11 and 12 has an angular shape as shown clearly in Figure 1; that is to say each of said pipes has 95 100

a forward portion 13 which is arranged substantially perpendicular within the compartment or chamber 7 above the wind chest, and a portion 14 which is arranged at an approximate right angle to the first mentioned portion. The portions 14 of the pipes 10, 11 and 12 are disposed substantially horizontal within the body portion 2 of the casing 1 of the organ, the horizontal portions of the pipes of the respective rows of pipes being arranged one above the other as shown clearly in Figure 1.

The pipes of the organ are of common construction, hence, need not be illustrated or described in detail herein, and also the toe portions of said pipes are seated in any suitable manner at apertures formed through the top wall of the wind chest whereby air may pass through said apertures from said wind chest into said pipes to cause said pipes to speak. The passage of air from the wind chest 8 into the pipes of the organ is controlled by valve units, preferably though not necessarily of the magnetic type, which are located at the apertures formed through the top wall of the wind chest and these valve units are under control of keys 15 forming parts of the key board B of the organ as is ordinarily the case. Also the key board B of the organ includes other keys such as the stop keys 16 which control operation of certain mechanisms of the pipe organ. The construction and arrangement of the means for cooperatively connecting the keys 15 of the key board B with the valve units, and the mechanisms associated with the stop keys 16 are very well known to persons familiar with the art to which this invention belongs and I, therefore, have not illustrated such means in the drawings nor will I refer to same to any greater length in this specification, it being understood that any of the various means employed for these purposes in modern pipe organs may be incorporated in my improved pipe organ.

The body portion 2 of the pipe organ A serves as a swell box, the top wall of said body portion being provided with a plurality of shutters 17 which are hingedly supported in the manner common to shutters of swell boxes whereby they may be adjusted to various positions and thus control the volume of sound issuing from the interior of the body portion of the casing wherein the pipes of the organ are located. Each of the shutters is pivotally connected to a reciprocal operating member 18 and this reciprocal operating member is in turn operatively connected to an operating element 19 which is located convenient to the position of the person playing the organ. In other words the operating element may be in the form of a lever as illustrated in the drawings, or if preferred said operating element 19 may have the form of a pedal. In either event, the operating ele-

ment serves as a means which permits the person operating the pipe organ to adjust the shutters 17 to various positions whereby the volume of sound passing through the top wall of the casing may be regulated thus increasing the flexibility and musical expression of the organ. 70

I claim:

1. A pipe organ comprising a casing shaped to resemble a grand piano, a plurality of pipes, all of said pipes being located within said casing, and a key board comprised of keys cooperatively associated with said pipes to permit sounding thereof, said casing including a horizontally disposed portion and a vertically disposed portion and certain of the individual pipes being located partly in said horizontal portion and partly in said vertical portion. 75 80

2. A pipe organ comprising a casing shaped to resemble a grand piano, a plurality of pipes, all of said pipes being located within said casing, a key board comprised of keys cooperatively associated with said pipes to permit sounding thereof, said casing including a horizontally disposed portion and a vertically disposed portion and certain of the individual pipes being located partly in said horizontal portion and partly in said vertical portion, and a wind chest located at the bottom of said vertical portion of said casing. 85 90 95

3. A pipe organ comprising a casing shaped to resemble a grand piano, a plurality of pipes, all of said pipes being located within said casing, a key board comprised of keys cooperatively associated with said pipes to permit sounding thereof, and adjustable shutters supported at the top wall of the casing to control the volume of sound issuing therefrom when the organ is being played, said casing including a horizontally disposed portion and a vertically disposed portion and certain of the individual pipes being located partly in the horizontal portion and partly in the vertical portion. 100 105 110

4. A pipe organ comprising a casing shaped to resemble a grand piano, a plurality of pipes, all of said pipes being located within said casing, a key board comprised of keys cooperatively associated with said pipes to permit sounding thereof, adjustable shutters supported at the top wall of the casing to control the volume of sound issuing therefrom when the organ is being played, and means for imparting movement to said shutters, said casing including a horizontally disposed portion and a vertically disposed portion and certain of the individual pipes being located partly in the horizontal portion and partly in the vertical portion. 115 120 125

In testimony whereof, I have hereunto set my hand.

HARRY F. WATERS.
